[57] ABSTRACT

In an apparatus of the type wherein ink under pressure is applied to a nozzle which is vibrated, and the ink emitted by the nozzle thereafter breaks down into ink drops which are charged in a charging tunnel in response to video signals, an arrangement for establishing the nozzle vibration frequency to be a function of the video signals' frequency and the shape of the video signals.

INK DROP WRITING SYSTEM WITH NOZZLE DRIVE FREQUENCY CONTROL

BACKGROUND OF THE INVENTION

1. Field of the Invention

This invention relates to apparatus for writing with ink drops which are charged by a video signal and directed through an electric field to be deflected in accordance with the charge, and more particularly to improvements therein.

2. Description of the Prior Art

An ink drop writing apparatus has been developed wherein ink is applied under pressure to a nozzle. The nozzle is vibrated or driven in response to synchronizing signals, provided at a selected nozzle drive frequency. The vibrated nozzle causes an ink jet, which is emitted therefrom to break up into uniform drops at a distance away from the tip of the nozzle. The rate of such drop formation is determined by the vibration rate. A means for charging each drop is provided at the location at which the ink stream begins to break into drops. This means usually is a conductive tube or cylinder. Video signals are applied between the nozzle and the cylinder in response to which a drop assumes a charge determined by the amplitude of the video signal at the time that the drop breaks away from the jet stream.

The drop thereafter passes through a fixed electric field, as a result of which it is deflected by an amount determined by the amplitude of the charge on the drop. At the boundary of the electric field there is positioned a writing medium upon which the drop falls. Since the deflection of the drop is determined by the charge on the drop, the arrangement enables one to write information with the ink which is carried by the video signal.

As previously stated, at the time that a drop separates from the fluid stream, the drops are charged by electrostatic induction. If the field established by the video signal is maintained while the drop separates, the drop will carry a charge determined by this video signal. Obviously, if the video signal is in the process of rising or falling or is not present at the time the drops separate, the charge on the drop will not be that of the video signal. In order to place specific charges on given drops, one must know when drop separation is occurring or the phasing of the drop formation relative to the video signal. In the absence of control over drop separation time, because of unpredictable phase changes in the ink drop formation, the uniformity and the fidelity of the printing are affected adversely.

Various systems have been proposed and designed to control drop phasing in order to improve the printing of such ink drop writing devices. Two such systems are described in U. S. Pat. Nos. 3,465,351 and 3,562,761. None of the prior art systems control drop phasing on the basis of the shape of the video signals on which the probability of proper drop charging greatly depends.

OBJECTS AND SUMMARY OF THE INVENTION

It is a primary object of the present invention to provide a new improved ink drop writing system.

Another object of the present invention is to provide a new ink drop writing system with a novel arrangement for drop phasing.

A further object of the present invention is to provide in an ink drop writing system a novel arrangement for

controlling the nozzle drive frequency so as to maximize the probability of proper drop charging.

These and other objects of the present invention are achieved by providing in an ink drop writing system an arrangement which establishes the nozzle drive at a frequency, i.e., the frequency at which the nozzle vibrates, to be a function of the frequency of the video signals, as well as the shape of such signals.

The novel features of the invention are set forth with 10 particularity in the appended claims. The invention will best be understood from the following description when read in conjunction with the accompanying drawings.

15 BRIEF DESCRIPTION OF THE DRAWINGS

FIG. 1 is a block diagram of a typical prior art ink drop writing system;

FIG. 2 is a diagram of a single video signal; and

20 FIG. 3 is a block diagram of one embodiment of an ink drop writing system in accordance with the present invention.

DESCRIPTION OF THE PREFERRED EMBODIMENTS

FIG. 1 is a schematic drawing of the presently known arrangement which is shown to afford a better understanding of the invention. An ink reservoir 10 provides ink under pressure to tubing 12 which is flexible. An 25 electromechanical transducer 14 is usually placed adjacent to or around the tubing. The transducer is driven in response to signals from a source 16. The transducer serves to vibrate and/or compress the tubing 12 in the region of the nozzle 18. This results in an ink jet 20 being emitted which at a short distance downstream breaks up into drops 22 which are formed at a rate determined by the frequency of the vibration. In the region where the stream 20 breaks down into drops, a charging tunnel 24 is provided. This comprises a conductive cylinder to which video signals from a video 30 signal source 26 are applied. The video signals establish a field within the charging tunnel so that the ink drops which are formed therein assume a charge determined by the amplitude of the video signal present at the time the drop separates from the ink jet 20.

35 Downstream of the charging tunnel there are usually placed a pair of electrodes 28 which are connected to a field bias source 30. As a result, there is established between the electrodes a constant electric field. The ink drops, which bear charges in accordance with the 40 video signal, enter this field and are deflected by an amount which is proportional to the amplitude of the charge. This enables intelligent writing to occur on a writing medium 32, which is moved at some synchronous rate past the electrodes. Drops which do not bear 45 a video charge are captured by a tube or trough 34 which is judiciously placed at one side so as to capture these drops. It leads to a waste reservoir 36. The paper 32 moves into the plane of the drawing whereby its motion, together with the deflection of the drops, may be used for forming intelligible characters.

50 As previously stated intelligible characters can only be formed if the drops are properly charged, which is achievable only with proper drop phasing. Alternately stated, proper drop charging can be achieved only when the frequencies of the video signals and the nozzle vibration or drive are in a proper relationship. In accordance with the present invention, unlike prior art

systems, the nozzle drive frequency is chosen as a function of the video signals' frequency, hereafter designated F_v , and the shape of such signals.

FIG. 2 to which reference is now made is a waveform diagram of a single video signal or pulse, the abscissa designating time and the ordinate amplitude or level in terms of volts. Each signal comprises an interval T_e during which the signal amplitude is at an established level, designated by line 40. The interval or time T_e is preceded and followed by a signal rise time T_r and a signal fall time T_f , respectively. The video period equaling $T_r + T_e$ is defined as T_v , and the total signal time is defined as T_b . The number of video periods T_v per second is defined as the video frequency and is designated as F_v .

In accordance with the present invention the nozzle is driven at a frequency, hereafter referred to as the drop frequency and designated F_d somewhat different than the video frequency F_v . This frequency difference has been found to prevent the system from being set in an improper phase or 'bad phase' condition for long periods of time, which if permitted to occur would result in unacceptable performance. It has been discovered that no more than one error on adjacent video pulses occurs if one of the following relationships is maintained:

$$F_d = F_v / (1 + F_v \times T_r), \quad (1)$$

or

$$F_d = F_v / (1 - F_v \times T_r). \quad (2)$$

F_d , as expressed in equation (2), is higher than F_v . It represents a drop period equal to T_e . If the following relationship is held:

$$F_d \times T_e \geq 1 \quad (3)$$

there will be one or more drops that separate from the stream during T_e , i.e., the interval of the flat top of the T_{pulse} . However if:

$$F_d \times T_e < 1 \quad (4)$$

there will be fewer drops than video pulses.

One can think of the drop separations as sampling of the video condition. If there are fewer samples taken than there are pulses to detect, it is obvious that some pulses will not be displayed as deflected drops. Then there will be missing spots in the construction of a character. If there are more samples taken than there are video pulses, there will be extra drops in the construction of a character but no needed drops will be missing. Based on these considerations it has been determined that near optimum results are achieved when

$$F_d \times T_e = 1 \quad (5)$$

and

$$F_d = F_v / (1 - F_v \times T_r). \quad (2)$$

By maintaining these conditions one insures that a drop separation occurs during T_e of each video pulse while keeping the number of the extra drops to a minimum.

For explanatory purposes let it be assumed that the video frequency $F_v = 16,500$ Hz. Thus, the video period T_v , which equals $T_r + T_e$, is equal to $1/16,500 = 60.6 \mu s$. Assuming that T_r is equal to $1 \mu s$, based on equation (2)

$$F_d = 16,500/1 - 16,500 \times 10^{-6} = 16,777 \text{ Hz.}$$

In practice F_v is a function of the character generation system and the desired character rate, and therefore is generally fixed. Based on the shape of the video pulses and F_v , F_d is determined in accordance with equation (2) and (5).

FIG. 3 to which reference is now made is a diagram of an embodiment of an ink drop writing system which incorporates the teachings of the present invention. Therein elements like those in FIG. 1 are designated by like numerals. In accordance with the present invention a drop frequency source 40 which is connected to transducer 14 is incorporated. Source 40 activates the transducer with signals at the drop frequency F_d which, once chosen as herebefore explained, remains constant and is not changed unless F_v or the video pulse shape is changed.

There has accordingly been shown and described herein an improved ink drop writing system. The improvement over the prior art is realized by the means for and method of controlling the relative frequencies of the video signals and the nozzle vibration to minimize the likelihood of improper charging of successive drops. Basically in accordance with the present invention the nozzle drive frequency, referred to as the drop frequency, is made to be a function of the video signal frequency and video signal waveshape.

It should be appreciated that various modifications and/or equivalents may be substituted for the arrangements as shown without departing from the true spirit of the invention. For example, herebefore F_d was described as being a function of T_r . This is based on the assumption that the rise time T_r is greater than the fall time T_f , which is typical of most video pulses. If however one were to use video pulses with a fall time greater than the rise time, T_f should be substituted for T_r in equation (2). Thus in general it may be stated that F_d is a function of F_v and the rise or fall times, whichever is greater. Also herebefore it was indicated that it is preferable to chose F_d in accordance with equation (2). In such a case, though extra drops may occur, one insures against any voids in the generated character. Clearly if one or more voids can be tolerated in the generated characters, F_d can be chosen in accordance with equation (1), i.e., $F_d = F_v / (1 + F_v \times T_r)$. Therefore all such modifications and equivalents are deemed to fall within the scope of the invention as defined in the appended claims.

60 What is claimed is:

1. In an ink drop writing system of the type wherein ink under pressure is delivered to a nozzle, a transducer vibrates the nozzle as a function of drive signals supplied thereto, the nozzle emits an ink jet which breaks up into drops, a charging tunnel is positioned in the region at which the ink jet breaks up into the drops, the charging tunnel being adapted to respond to video sig-

nals to charge the drops passing therethrough as a function of said video signals, the improvement comprising: video pulse signal source means coupled to said charging tunnel for applying video signals thereto at a preselected first frequency; and nozzle drive means for applying drive signals to said transducer at a second frequency to vibrate said nozzle therewith, said second frequency being a function of said first frequency and the rise or fall time of said video pulse signals.

2. The arrangement as recited in claim 1 wherein said second frequency is higher than said first frequency.

3. In an ink drop writing system of the type wherein ink under pressure is delivered to a nozzle, a transducer vibrates the nozzle as a function of drive signals supplied thereto, the nozzle emits an ink jet which breaks up into drops, a charging tunnel is positioned in the region at which the ink jet breaks up into the drops, the charging tunnel being adapted to respond to video signals to charge the drops passing therethrough as a function of said video signals, the improvement comprising: video signal source means coupled to said charging tunnel for applying video signals thereto at a preselected first frequency; and nozzle drive means for applying drive signals to said transducer at a second frequency to vibrate said nozzle therewith, said second frequency being a function of said first frequency and the shape of said video signals, the duration of each video signal being characterized by a first time interval during which the level of the signal rises from a reference

level to a selected level, a second time interval, following said first time interval, during which the signal level is at said selected level, and a third time interval, following said second time interval, during which said signal level falls from said selected level to said reference level, said first and third time intervals being definable as the rise and fall times of the signal, respectively, said second frequency being a function of at least said first frequency and said rise time.

4. The arrangement as recited in claim 3 wherein $F_d = F_v/1 - F_v T_r$, where F_v and F_d are the first and second frequencies respectively, and T_r is said rise time.

5. The arrangement as recited in claim 3 wherein the second frequency, definable as F_d is higher than said first frequency, and $F_d T_e$ is not less than 1, where T_e represents said second time interval.

6. The arrangement as recited in claim 3 wherein $F_d = F_v/(1 - F_v T_x)$, where F_v and F_d are the first and second frequencies respectively, and T_x is the greater of said rise time and fall time.

7. The arrangement as recited in claim 6 wherein the second frequency, F_d is higher than said first frequency and $F_d T_e$ is not less than 1, where T_e is said second time interval.

8. The arrangement as recited in claim 3 wherein $F_d = F_v/(1 - F_v T_x)$ where F_v and F_d are the first and second frequencies respectively, and T_x is the greater of said rise time and fall time.

UNITED STATES PATENT OFFICE
CERTIFICATE OF CORRECTION

Patent No. 3,736,593 Dated May 29, 1973

Inventor(s) ROBERT I. KEUR, ET. AL.

It is certified that error appears in the above-identified patent and that said Letters Patent are hereby corrected as shown below:

Column 3, line 45 should read as follows: -- video pulse. However if: -- . Column 4, line 11, the denominator of the fraction should be enclosed in parenthesis and should appear as follows: -- $16,500/(1-16,500 \times 10^{-6})$ -- . Column 6, line 12, the denominator of the fraction should be in parenthesis and should appear as follows: -- $F_v/(1-F_v T_r)$ -- .
